[**] Term: 14 Years

[57] CLAIM

[21] Appl. No.: 855,937

The ornamental design for an anti-skid tire traction unit,
as shown and described.

[22] Filed: Mar. 23, 1992

DESCRIPTION

[52] U.S. Cl. D12/154

FIG. 1 is a front elevational view of an anti-skid tire
traction unit showing my new design;
FIG. 2 is a rear elevational view thereof;
FIG. 3 is a top plan view thereof;
FIG. 4 is a side elevational view thereof, the opposite
side being a mirror image of that shown; and,
FIG. 5 is an enlarged fragmentary front elevational
view thereof.[58] Field of Search D2/154; 152/221, 222,
